(57) CLAIM

The ornamental design for a house facade, as shown and described.

DESCRIPTION

FIG. 1 is a front elevational view of the house facade of the present invention;

FIG. 2 is a left side elevational view thereof;

FIG. 3 is a right side elevational view thereof; and,

FIG. 4 is a rear elevational view thereof.

The broken lines are for illustrative purposes only and form no part of the claimed design.
